UNITED STATES PATENT OFFICE.

SAMUEL J. SHIMER, OF MILTON, PENNSYLVANIA.

CUTTER-HEAD.

SPECIFICATION forming part of Letters Patent No. 650,764, dated May 29, 1900.

Application filed March 26, 1900. Serial No. 10,231. (No model.)

To all whom it may concern:

Be it known that I, SAMUEL J. SHIMER, a citizen of the United States, residing at Milton, in the county of Northumberland and State 5 of Pennsylvania, have invented new and useful Improvements in Cutter-Heads, of which the following is a specification.

My present invention relates to cutter-heads; and the objects of the same are to provide efficient means for properly dividing or distributing the work which each bit or cutter is required to do in cutting a tongue or groove in lumber with a view to giving to the bits which have the major portion of the work 10 to do a comparatively-large seat upon the cutter-head in the line of cut and to so distribute the strain on the holding-bolts that the work may be accomplished on hard wood without turning the cutters out of adjustment. In order to accomplish these desirable 15 objects, I have formed two bit-seats within the limit of each quarter-section of the cutter-head, and I have also located each alternate pair of bits or cutters upon opposite sides of 20 an expansible cutter-head, so that each side of the cutter-head is provided with two pairs of cutters. By this arrangement I am enabled to divide the work of cutting a tongue into four parts, two upon each side of the 25 tongue to be cut, and in this way the work is equally and properly distributed around the cutter-head without undue strain at any one point. Heretofore circular bits made to 30 cut a single tongue or groove were divided in two parts and each set at an opposite incline for clearance, one part cutting all above the center line of the tongue and the other cutting all below the center line of the tongue and overlapping within the space the tongue 35 occupies. This construction made it necessary to form the tongue-bit seat upon the smallest bit diameter. In order to make the two cutting edges upon such a circular bit, the notch in it must be cut deep enough 40 to form the inner cutting edge, below which and within the inner circle of the bit the seat limit is confined. It therefore follows that the tongue-forming section of such a circular tongue-bit is limited in its seat-surface 45 to the small base that goes within the smallest cutting diameter of such tongue-bit.

In the accompanying drawings, which form

a part of this specification, Figure 1 is a perspective view of a cutter-head made in accordance with my invention. Fig. 2 is a bottom plan view of the same. Fig. 3 is a perspective view of the head with the cutters removed and the parts separated. Fig. 4 is a perspective view of one of the cutters. Fig. 5 is a similar view of the companion cutter. Fig. 6 is a perspective view of the bolt.

Like numerals of reference designate like parts wherever they occur in the different views.

In the drawings the numeral 1 designates 65 the upper section of the cutter-head, and 2 the lower section of the same. On each section of the head two segmental portions 3 are formed. When the two sections of the cutter-head are in operative position, these segments 70 3 each form a quarter-section of the cutter-head, and formed within each segment are two bit-seats 4 5. These seats are arranged in pairs, each pair being located in a segment or quarter-section 3 of the head and the seat 75 4 being of larger area or diameter than the seat 5. The bit 6 is fitted to the seat 4 and is held in adjusted position by the bolt 7. The smaller bit 8 is held in the seat 5 by the bolt 9. It will be noted that the seats 4 in each section 80 of the head are located diagonally opposite each other and are oppositely inclined, while the seats 5 are also similarly disposed and inclined. Every alternate pair of seats on the opposite sides of the head are reversely inclined. 85 The bits 6 cut the lower half and shoulder of the tongue and the bits 8 cut the round corners and the outer edge of the tongue, the cutting edges of each pair of bits overlapping. By this arrangement the bit 6, which cuts the 90 larger area of the tongue, is provided with a seat of proportionately-larger area than the seat 5 for the bit 8, and the result is that an equitable division of the work and a proper distribution of the strain are accomplished. 95 Another advantage of this arrangement is that the cutting edge of the bit 8 may be adjusted to cut a tongue of more or less length independently of the adjustment of the bit 6. In fact, the bits are independently adjustable for depth of cut, and when seated, as described, in an expansible head adjustment in 100 width of tongue as well as depth can be readily accomplished.

Having thus fully described my invention, what I claim is—

1. In a cutter-head, circular bit-seats arranged in pairs within the limit of each quarter-section around the head, each alternate pair of seats being upon opposite sides of the head, each pair of seats consisting of a large and a smaller seat, and circular cutters secured in said seats, substantially as described.

2. In an expansible cutter-head, a series of circular bit-seats arranged alternately in pairs upon opposite sides of the head, and independently-adjustable bits secured in said seats, the bits of each pair being of different size to fit corresponding seats, as and for the purpose described.

3. A cutter-head comprising two sections adapted to be relatively adjusted, bit-seats arranged in pairs alternately upon opposite sides of said sections, each pair of seats occupying a quarter-section of the cutter-head, each seat in each pair being different in size from its fellow, and independently-adjustable cutters secured in the seats, substantially as described. 20 25

In testimony whereof I have hereunto set my hand in presence of two subscribing witnesses.

SAMUEL J. SHIMER.
